UNITED STATES PATENT OFFICE.

ROBERT SPENCER AND CHARLES C. BLAND, OF TERRE HAUTE, INDIANA.

FRESH-AIR BED.

1,144,075.

Specification of Letters Patent. Patented June 22, 1915.

Application filed July 29, 1911. Serial No. 641,293.

To all whom it may concern:

Be it known that we, ROBERT SPENCER and CHARLES C. BLAND, citizens of the United States, residing at Terre Haute, in the 5 county of Vigo and State of Indiana, have invented certain new and useful Improvements in Fresh-Air Beds, of which the following is a specification.

This invention relates to beds, contemplat- 10 ing in particular the production of a portable swinging bed adapted for use out of doors.

One essential of the invention is an insect- 15 proof bed inclosure provided with a stable bed frame, the inclosure being supported for swinging movement in a portable framework.

Another salient feature resides in means to 20 lock the bed inclosure against swinging movement when desired.

One object of the invention is the produc- 25 tion of a bed which will enable the user thereof, as an invalid, for instance, to get the benefit derived from out-of-door sleeping or rest and a perfectly unimpeded circulation 30 of fresh air and at the same time to be effectually protected from annoyance by insects, and enabled to avoid the frequently experienced lack of proper fresh air circu- lation or drafts incident to indoor sleeping.

Another object is to provide a fresh-air 35 bed of simple construction which can be conveniently and readily moved wherever desired in order that the user may take advan- tage of a breeze from any direction or of 40 the shade of a tree or the like, and which can be employed as a swinging crib if desired.

The invention will now be described in the 45 following specification, taken in connection with the accompanying drawings, and then more particularly pointed out in the appended claims.

In the drawings, Figure 1 is a perspective 50 view, partly broken away, showing our im- proved fresh-air bed, and Fig. 2 is a side elevation, partly broken, showing the means 55 for locking the bed inclosure against swing- ing movement.

Referring now to the drawings, wherein 60 similar parts are denoted by similar char- acters of reference throughout the several views, 65 1 denotes a supporting framework comprising base-beam 2, stanchions 3 and hang- beam 4, the several parts of the structure be- 70 ing permanently connected or, if preferred, held to assembled relation through the me-

dium of removable bolts to provide for ready disengagement for storage or shipping purposes as may be found expedient. The framework, while of strong and stable construction is designed to be of sufficient light- 60 ness to enable the structure, when supporting the bed in operative position, to be readily and easily moved as found desirable or convenient. An approximately rectan- 65 gular bed-inclosing element comprises a skeleton frame 5, formed of material of appropriate proportions, tautly connected to which are screen sections 6, formed of non- rusting material and of sufficiently fine mesh 70 to effectually exclude mosquitoes, flies, and the like, the several screen sections forming the sides and ends of the bed inclosure, as clearly shown in Fig. 1 of the drawings, one of the sides including a hinged door 7. 75 The bed inclosure is supported for swinging movement between the stanchions 3 by means of a plurality of supporting rings 8 attached to the hang beam 4 and co-operating hooks 9 connected to metal straps 10 fixedly strad- 80 dling that edge of the inclosure common to the uppermost sides of the same when said inclosure is in suspended operative position, said rings and hooks being adapted for ready disengagement when found desirable to disconnect the bed inclosure from its support- 85 ing frame.

11 denotes a locking-rod comprising sec- tions 12 and 13 pivotally connected at 14 and disposed along one stanchion 3 and the base 90 beam respectively, section 13 being pivotally mounted on the latter at 15 and terminally provided with an upwardly-extending lock- 95 ing lug 16 passing through aperture 17 in said beam and designed to engage locking 100 aperture 18 formed in a locking plate 19 secured to the bed inclosure and lock the lat- 105 ter against swinging movement when de- sired. Section 12 is operatively held to its co-operating stanchion 3 for movement lon- gitudinally thereof in any suitable manner, as by staples or the like, and is provided on its upper end with an operating ring or handle 20 and, adjacent said ring, with a retaining notch 21 designed, when the said 110 section is moved to the limit of its upward movement, to engage pin 22 projecting from the stanchion and maintain lug 16 out of locking engagement with aperture 18 and permit the bed inclosure to be swung if de- sired, section 12 of the locking rod, through its weight, when free, normally holding said

lug in said aperture. Disposed within the bed inclosure, preferably below the horizontal median line thereof, and either permanently attached thereto or adapted for removal, is a bed frame 23 designed of course to support the bed furnishings of the user. It is to be observed that the method of supporting the bed inclosure, that is, from an edge common to two of the sides of said inclosure provides for easy swinging of the latter with but little effort and also insures a closed position of the door 7 during said swinging without providing a catch for the door. The user of the bed effects his entrance by simply swinging the inclosure a short distance from himself, thus lowering the door, lifting the latter and stepping upon the outer rail of the bed frame, the door, at the termination of said entrance, falling to closed position and the inclosure swinging to normal upright position, while the occupant, without emerging from the inclosure can, by lifting the door a short distance, easily reach operating handle 20 and maintain the bed against movement, if desired.

From the above description it will be noted that the particular form and manner of supporting the bed closure is important. First in providing below the bed proper a ventilating space which is fully screened and protected; secondly in providing a gradually-increasing width for a considerable distance above the bed proper; and thirdly, in arranging the upper bar as a support for an opaque covering where shade or darkness is required, the divergent sides of the closure properly supporting and carrying such covering without other fastening means.

From the above it will be seen that we have provided a simple, convenient and readily portable fresh-air bed adapted for

the use of invalids if desired or, in conformity with the modern doctrine of the 45 benefit of out-door sleeping generally, adapted to replace the ordinary in-door bed.

Having thus described our invention, what we claim and desire to secure by Letters Patent, is:—

The combination with a main frame including uprights and upper and lower cross-bars connecting said uprights, of a diamond-shaped screen-covered bed inclosure, a door comprising one of the upper faces of said 55 diamond shaped bed inclosure and wholly below said upper cross bar, whereby it is normally held closed by gravity, means removably connecting one of the major-length members of said diamond-shaped bed inclosure to the upper cross-bar to swingingly 60 suspend said inclosure from the upper cross-bar and between and free of contact with the uprights, a bed support arranged in said inclosure between the lowermost edge 65 thereof and the point of maximum width of said inclosure, and means coöperating with the inclosure to fix the inclosure with relation to the main frame, said means engaging the inclosure on the line diagonally 70 opposed to the point of connection of said inclosure to the upper cross-bar, whereby when the inclosure is fixed with relation to the main frame the bed support is maintained horizontal and the space within the 75 inclosure above the bed support is of gradually increasing width for a portion of its height.

In testimony whereof, we affix our signatures in presence of two witnesses.

ROBERT SPENCER.
CHARLES C. BLAND.
